UNITED STATES PATENT OFFICE.

AUGUSTUS D. LAURENT, OF WESTFIELD, NEW JERSEY.

RULE.

1,360,539.

Specification of Letters Patent. Patented Nov. 30, 1920.

Application filed May 26, 1919. Serial No. 299,737.

To all whom it may concern:

Be it known that I, AUGUSTUS D. LAURENT, a citizen of the United States, residing at Westfield, in the county of Union and 5 State of New Jersey, have invented new and useful Improvements in Rules, of which the following is a specification.

This invention relates to improvements in rules and the principal object of the invention is to provide means for holding the portions 10 of a rule at different angles whereby the rule may be used as a square.

Another object of the invention is to locate the locking means within the parts of the 15 rule so that said locking means will not interfere with the ordinary use of the rule.

The invention also consists in certain other features of construction and in the combination and arrangement of the several 20 parts, to be hereinafter fully described, illustrated in the accompanying drawings and specifically pointed out in the appended claim.

In describing my invention in detail, reference will be had to the accompanying 25 drawings wherein like characters denote like or corresponding parts throughout the several views, and in which:—

Figure 1 is a view showing a rule supplied 30 with my invention;

Fig. 2 is a part sectional view;

Fig. 3 is a detail view.

In these views 1 indicates one of the half 35 portions of a rule and 2 indicates the other half portion, these portions being pivotally connected together by the usual hinge means which consists of the cylindrical part 3 which fits between the disks 4 carried by the other part and the pin 5 which connects the 40 said cylindrical part and disk together. In carrying out my invention I form a hole 6 in the inner end of the part 2 and place in said hole a screw bolt 7. The screw part of this bolt is engaged by a disk 8 which 45 has a portion thereof projecting through a recess 9 formed in the part 2 of the rule and communicating with the hole 6 so that the

knurled edge of said disk will slightly project above the face of the rule so the same may be turned by the thumb or finger to move the bolt longitudinally. The bolt is prevented from rotating by means of a small pin 7' carried by said bolt and passing through a slot 2' formed in the rule. The cylindrical part 3 is provided with holes 10 50 which are adapted to register with the outer end of the hole 6 so that the bolt 7 may engage one of these holes and thus lock the two parts of the rule against further movement. It will thus be seen that by engaging the bolt with the different holes the two parts of the rule may be held at any desired angle. As the parts forming my invention are inclosed within the body of the rule they 55 will not interfere with the ordinary use of the rule.

It is thought from the foregoing description that the advantages and novel features of my invention will be readily apparent.

I desire it to be understood that I may 70 make changes in the construction and in the combination and arrangement of the several parts, provided that such changes fall within the scope of the appended claim.

What I claim is:—

A foldable rule having its hinge composed 75 of a cylindrical part carried by one member and a pair of disks carried by the other member, said cylindrical part having a plurality of holes extending inwardly from portions of its periphery, the part carrying the disks having a longitudinally extending hole therein and a laterally extending recess in communication with said hole, a screw bolt 80 in said hole, a knurled disk located in the recess and having a screw threaded aperture engaging the bolt and moving the same into and out of engagement with any one of the holes in the cylindrical part of the hinge, 85 said disk having a portion projecting from one face of the rule and means for preventing rotation of the bolt.

AUGUSTUS D. LAURENT.
